PACKAGE OPENER

William H. Brown, Fremont, Ohio, assignor to Clauss Cutlery Company, Fremont, Ohio, a corporation of Ohio

Application April 9, 1957, Serial No. 651,630

1 Claim. (Cl. 30—2)

This invention pertains to apparatus for cutting the surface of an article and has particular adaptability for opening a package by separating a wall thereof from the remaining walls.

The opening of packages to gain access to the contents thereof in an easy manner and with expedience has posed a problem for as long as packages or enclosed containers have been in existence. This problem has plagued the manufacturer of the package, the producer of the contents, and the ultimate recipient of the combination.

The problem has frequently been attacked, in the case of packages for consumer goods, by fabricating the packages with "built-in" devices for expediting access to the contents, including perforated walls, sealed-in tapes that rip a slot in a wall of the package when pulled outwardly, and various types of quick opening fasteners. These devices have met with varying degrees of success but have inherently resulted either in adding to the cost of the package with a resulting increase in the price of the goods to the consumer, or a narrowing of the profit margin for the manufacturer, middlemen, and/or retailer. For contents of a distinct nature or of considerable value, slight increases in the cost and price of the package from using these "built-in" openers, which generally amount to one or two cents at a maximum, are no detriment to the salability of the articles and may be more than offset by the appeal to the consumer of the easy opening feature of the package. For standard items or those of low value, however, a slight increase in the price will likely turn the consumer to other brands with the result that the cost of the easy opening feature will not be passed onto the consumer. This extra cost will, therefore, be absorbed in the profit margins and the "built-in" opener will likely not be used. In addition to packages directly enclosing consumer goods, shipping containers, with corrugated cardboard walls or the like, are also difficult to open. It will be readily appreciated that shipping containers cannot, of necessity, employ built-in openers as such would encourage pilfering of the contents in the mail. The majority of packages are therefore, for one reason or another, of the conventional type with no easy means of access.

To relieve the ultimate recipient of the usual time consuming and energy dissipating operation of package opening, often resulting in broken fingernails, painful paper cuts, or more or less conventional cuts from the employment of knives to facilitate opening which frequently damage contents, too, a new package opener has been developed that is especially safe to use, quick in operation, easy to employ, comfortable to grasp, and attractive. These features produce a readily salable item to consumers. Accordingly, a great many kitchens or workshops will include the device as standard equipment resulting in a boon not only for the ultimate package recipient but for the package or content manufacturer who will be considerably less plagued with the problem of built-in openers in their packages, the consumers or recipients now having a dependable, safe, efficient device

2

at their disposal with which to gain access to the interior of the package.

The new opener is also advantageous for those employed in opening a great number of packages each working day, including food handlers in supermarkets and corporation mail handlers.

It is an object of the invention to provide a package opener that is safe.

Another object of the invention is to provide an opener capable of producing an incision in a package quickly.

A further object is to provide an opener that is easy to operate.

An additional object is to provide an opener which is comfortable to use.

Other objects and advantages will appear from the following detailed description of a preferred embodiment of the invention, reference being made to the accompanying drawing, in which—

Figure 1 is an isometric view of apparatus embodying the invention;

Fig. 2 is a side, elevational view of the apparatus of Fig. 1;

Fig. 3 is a front, elevational view of the apparatus of Fig. 1;

Fig. 4 is a top view of the apparatus of Fig. 1;

Figs. 5, 6 and 8 are cross-sectional views on lines 5—5,

6—6 and 8—8 respectively, of Fig. 2; and

Fig. 7 is an elevational view of a cutting blade that may be used with the apparatus.

Referring to the drawing, opener 11 comprises a handle 12, and a cutting unit 13. Handle 12 in the form shown on the drawing has a rounded rear edge 14 and a rounded forward edge 15 connected by a rib 16, forward edge 15 having a convoluted shape to comfortably conform to two or more fingers of a human hand.

The cutting unit 13 comprises a first wall contacting portion 17 and a second wall contacting and guiding portion 18. A cutting blade 20 projects from the first portion and is affixed in the opener in any suitable manner preferably by being inserted in slot 21 of a relatively thick portion 22 located immediately below portion 17. Portion 22 also contains a tapered hole located laterally to slot 21 and extending contiguous to the slot in such a manner that a tapered pin 23 forced into the hole wedges firmly between the side of the hole and the blade, thereby securely holding the blade.

The upper edge of the blade 20 preferably terminates below a plane passing between the extremities of portions 17 and 18. This is of considerable value as a safety feature since portions 17 and 18 thus aid in preventing the cutting unit from cutting anything that it may come in contact with by a careless "swipe" of the opener. It maybe noted that an article, in order to be cut, must be projected inside the space defined by the two portions and the aforementioned plane. The blade should, however, project a sufficient distance outwardly from the face 17 to be capable of cutting completely through the wall of the package. In practice, the distance is slightly greater than the thickness of standard corrugated cardboard used in shipping containers.

Referring to Fig. 4, the blade 20 is set at angle "A" with respect to the surface of the guiding portion 18. This angle locates the cutting edge divergently with respect to the portion so that, as the opener is moved parallel to the edge of the package, the cutting edge will tend to move the opener away from this edge. This maintains the guiding portion 18 against the adjacent wall and overcomes any tendency for the blade to "drift" outwardly toward the edge of the package. The only force needed to move the opener, therefore, is in a direction parallel to the path of the opener since no lateral force is necessary to maintain portion 18 against the

corresponding wall. The angle of the blade with respect to portion 18 is preferably in the order of two degrees. It is desirable to use an angle that is just sufficient to maintain portion 18 in contact with the wall as any further increase in this angle will result in excessive binding force between portion 18 and the corresponding wall and excessive friction between the blade and the surface being cut.

A study has shown that there is a definite tendency, when an incision is made, to hold the opener with a lead angle, that is with the handle extending forwardly of the cutter. This causes the leading edge of portion 17 to dig into the wall and substantially increase the force necessary to pull the opener. As a result of this discovery, referring to Fig. 2, portion 17 is located with lead angle "B" with respect to a plane perpendicular to the handle. This angle permits portion 17 to be flush with the surface when the handle is maintained at an angle ahead of the cutter. The leading edge of this portion thus moves smoothly along the surface with a minimum of force required and with no tendency to dig into the surface. Angle "B" may be of any reasonable amount but in practice, an angle of 6° has been found to give the best performance. Angles up to approximately 30° function satisfactorily, however. Above this amount, the hand of the operator grasping the opener may be cocked in an uncomfortable position.

The cutting edge of the blade is maintained at an angle to the package wall to facilitate making the incision. This edge is therefore disposed diagonally to the longitudinal extent of the blade and faced generally toward the direction of movement. The lower termination of the edge is located at or slightly above the face of portion 17.

In operation of the opener, it is grasped, preferably by the right hand, with the fingers encompassing the convoluted edge 15 and the thumb extending toward the outer surface of portion 18. The inner surface of portion 18, closer to the blade 20, is then placed contiguous to the wall or top of the package which is to be separated from the other walls. The opener is then thrust toward the package with blade 20 piercing the adjacent wall until the face of portion 17 comes in contact with it. The opener is then guided along the package, being maintained parallel to the junction of the two walls by the coaction of portion 18 and its corresponding wall. The opener is preferably pulled toward the operator with either the package being moved in relation to the operator or the operator moving in relation to the package, depending on the weight of it. Preferably, three of the four walls of the package are cut so that the top or other wall may be rotated away from the remaining portion, the junction of the top and fourth wall acting as a hinge. Only a light force is necessary to operate the opener and

this force need be maintained only in the direction of movement.

The opener thus comprises a first portion adapted to contact and be moved along a first wall in which an incision is to be made, and a second or guiding portion adapted to contact and be moved along a second wall adjacent, and disposed at an angle to, the first wall. The first portion has a blade extending therefrom a distance at least as great as the thickness of the wall to be cut. This blade is at an angle to the second portion, diverging outwardly toward the direction of movement. A handle is fixedly attached to that side of the first portion opposite the side contacting the first wall, the first portion being at an angle to a plane perpendicular to the handle and inclined toward the direction of movement of the opener.

The above description has been intended to serve in an illustrative and not a limiting sense, the scope of the invention being limited only by the depending claim.

What I claim is:

An opener for domestic use for opening lightweight packages or the like having at least two walls disposed at an angle to one another, said opener comprising a first portion adapted to contact a first wall, a second portion connected to said first portion and adapted to contact a second wall adjacent, and disposed at an angle to, said first wall, a blade extending outwardly from said first portion, a handle fixedly attached to that side of said first portion opposite the wall contacting side, said handle being inclined at an angle of not more than about 30 degrees toward the direction of movement of said opener when said first portion is parallel to the corresponding wall, said handle having a lateral cross section generally in the shape of an "I" of varying dimensions over the length of the handle with the web of the "I" extending laterally to the direction of movement of said opener, said "I" being thicker nearer the first wall contacting portion with a slot extending thereinto from said first portion to receive said blade, said handle having a tapered hole extending toward and contiguously to said slot, and a tapered pin in said tapered hole to wedge said blade securely in said slot.
